UNITED STATES PATENT OFFICE

CHARLES L. CUTLER, JR., OF MARLBORO, MASSACHUSETTS

HOT AIR HEATER

Application filed February 27, 1930. Serial No. 431,744.

This invention relates to hot air heaters and particularly to devices of this character which may be installed in a cabinet formed of insulating material and has for its object 5 the production of a heater in which the air admitted thereto may be heated to high degree of temperature with a minimum expenditure of oil in the oil burner utilized therewith.

10 This object is attained by the mechanism illustrated in the accompanying drawings.

For the purpose of illustrating the invention, one preferred form thereof is illustrated in the drawings, this form having been 15 found to give satisfactory and reliable results, although it is to be understood that the various instrumentalities of which the invention consists can be variously arranged and organized, and the invention is not limited 20 to the precise arrangement and organization of these instrumentalities as herein shown and described except as required by the scope of the appended claims.

25 Of the drawings: Figure 1 represents a vertical section of a hot air heater embodying the principles of the present invention, the cutting plane being on line 1, 1, on Fig. 2.

Figure 2 represents a horizontal section 30 of same on line 2, 2, on Fig. 1.

Figure 3 represents a horizontal section of same on line 3, 3, on Fig. 1.

Figure 4 represents a vertical transverse section on line 4, 4, on Fig. 1, and

35 Figure 5 represents a sectional detail showing how the hot air pipes are mounted in the partitions and the unions are connected thereto.

Similar characters indicate like parts 40 throughout the several figures of the drawings.

In the drawings, 10 is a cabinet, the side and top walls of which are formed of insulating material adapted to prevent the escape of heat therefrom.

45 Within the cabinet and parallel with the end walls thereof are metal partitions 11 extending from the bottom of the cabinet to the top wall thereof.

50 These partitions 11 are spaced from the

end walls of the cabinet and form compartments 12 entirely closed.

These compartments are filled with dead air which has no circulation.

Between the partitions 11 are a plurality 55 of pipes 13, the ends of which extend through the partitions 11 and are connected in series by unions 14 within the compartments 12.

By means of these unions a continuous conduit is formed, the lower end of which communicates with a pipe 13 through which cold air is admitted to said conduit.

The upper end of the conduit has an elbow 16 connected thereto within a compartment 12 and from this elbow extends a pipe 17 60 65 through which the heated air passes upwardly to the registers in the various rooms of the house or apartment in which the cabinet is installed.

In the lower end of the cabinet 10 and 70 beneath the pipes 13 are oil burners 18, one or both of which may be used to heat the air passing through the conduit 13, 14.

Access to the burners is obtained through 75 the door 19 in the front wall of the cabinet 10 and on either side of the door 19 are openings 20 for the admission of air to the burners.

Between the rear burner 18 and the lower 80 pipe 13 is a curved baffle plate 21 extending from one end partition 11 to the other end partition.

85 Back of the burners 18 and parallel with the rear wall of the cabinet is a metal partition 22 extending from the bottom of the cabinet to a point near the top wall of said cabinet, as shown in Fig. 4.

This partition 22 is spaced from the rear wall of the cabinet thereby forming a passage 23 communicating near its lower end with an exit pipe 24 leading to the chimney flue.

90 This exit pipe 24 has a branch pipe 25 extending therefrom and communicating with 95 the passage 23 near the top of the partition 22.

95 This branch pipe 25 is provided with a valve or damper 26 which may be closed when the heater is in operation and it is de- 100

sired to have the products of combustion enter the pipe 24 at its lowest end.

The baffle plate 21 is curved in such a manner that the products of combustion from the oil burner 18 will be deflected upwardly into contact with the various pipes 13 to be discharged at 27 into the upper end of the passage 23.

Each partition 11 is provided with an annular flange 28 surrounding the end of each pipe 13, and each pipe is provided near each end thereof with a stud 29 adapted to contact with the inner faces of the partitions 11 to prevent any end movement of said pipes relatively to said partitions 11.

All of the products of combustion from the oil burners 18 are confined within the chamber formed by the front wall of the cabinet, the end partitions 11, and the back partition 22, so that all of the pipes 13 disposed between the partitions 11 are subjected to these products of combustion.

As a consequence the cold air first admitted to the lower pipes will be heated to some extent and as this air partially heated moves upwardly through the conduit 13, 14, it will be subjected to more and more heat until it passes from the upper pipe 13 into the vertical pipe 17.

At this time it will be intensely heated.

The products of combustion from the burner 18 will also heat the end partitions 11 and back partition 22, and this heat will radiate from these partitions into contact with the pipes 13, thereby greatly assisting in the heating of the air passing through said pipes.

By means of the construction herein shown which may be constructed at little cost, a great quantity of hot air may be provided sufficient to heat several rooms with a minimum expenditure of oil in the oil burners.

It is believed that the operation and many advantages of the invention will be understood without further description.

Having thus described my invention, I claim:

1. The combination of a cabinet having top, side and end walls of insulating material; partitions therein parallel with and spaced from the end walls of said cabinet; a plurality of substantially horizontal pipes extending through both said partitions; unions connecting the projecting ends of said pipes to form a continuous conduit extending upwardly within said cabinet; means for admitting cold air to the lower end of said conduit; an outlet from said conduit extending from the upper end of said cabinet, and a heat producing device directly beneath said conduit.

2. The combination of a cabinet having top, side and end walls of insulating material, metal partitions therein parallel with and spaced from the end walls thereof; a plurality of pipes extending through said

partitions; unions connecting the projecting ends of said pipes to form a continuous conduit extending upwardly within said cabinet; means for admitting cold air to the lower end of said conduit; an outlet from said conduit extending from the upper end of said cabinet, and an oil burner beneath said conduit.

3. The combination of a cabinet having top, side and end walls of insulating material; metal partitions therein parallel with and spaced from the end walls of said cabinet; a plurality of pipes extending through both said partitions; unions connecting the projecting ends of said pipes to form a continuous conduit extending upwardly within said cabinet; means for admitting cold air to the lower end of said conduit; a baffle plate beneath the lower pipe; an outlet from said conduit extending from the upper end of said cabinet and an oil burner beneath said baffle plate.

4. The combination of a cabinet having top, side and end walls of insulating material; metal partitions therein parallel with and spaced from the end walls of said cabinet; a plurality of pipes extending through both said partitions; unions connecting the projecting ends of said pipes to form a continuous conduit extending upwardly within said cabinet; means for admitting cold air to the lower end of said conduit; a metal partition between said end partitions and spaced from the back wall of said cabinet, said partition extending from the bottom of the cabinet to a point adjacent the top wall thereof; an outlet from said conduit extending from the upper end of said cabinet and a heat producing device directly beneath said conduit.

5. The combination of a cabinet having top, side and end walls of insulating material; metal partitions therein parallel with and spaced from the end walls of said cabinet; a plurality of pipes extending through both said partitions; unions connecting the projecting ends of said pipes to form a continuous conduit extending upwardly within said cabinet; means for admitting cold air to the lower end of said conduit; a metal partition between said end partitions and spaced from the back wall of said cabinet, said partition extending from the bottom of the cabinet to a point adjacent the top wall thereof; an oil burner; means for deflecting the products of combustion from said burner to the exit above said back partition; and an outlet from said conduit extending from the upper end of said cabinet.

6. The combination of a cabinet having top, side and end walls of insulating material; metal partitions therein parallel with and spaced from the end walls of said cabinet; a plurality of pipes extending through both said partitions; unions connecting the projecting ends of said pipes to form a con-

- tinuous conduit extending upwardly within said cabinet; means for admitting cold air to the lower end of said conduit; a metal partition between said end partitions and spaced from the back wall of said cabinet, said partition extending from the bottom of the cabinet to a point adjacent the top wall thereof; a pipe extending from the lower end of the back wall of said cabinet for the exit of the products of combustion; an outlet from said conduit extending from the upper end of said cabinet, and a heat producing device directly beneath said conduit.
7. The combination of a cabinet having top, side and end walls of insulating material; metal partitions therein parallel with and spaced from the end walls of said cabinet; a plurality of pipes extending through both said partitions; unions connecting the projecting ends of said pipes to form a continuous conduit extending upwardly within said cabinet; means for admitting cold air to the lower end of said conduit; a metal partition between said end partitions and spaced from the back wall of said cabinet, said partition extending from the bottom of the cabinet to a point adjacent the top wall thereof; a pipe extending from the lower end of the back wall of said cabinet for the exit of the products of combustion; a branch valved pipe from said exit pipe extending through the back wall of the cabinet near the top of said back partition; an outlet from said conduit extending from the upper end of said cabinet, and a heat producing device directly beneath said conduit.
8. The combination of a cabinet having top, side and end walls of insulating material; metal partitions therein parallel with and spaced from the end walls of said cabinet; a plurality of pipes extending through both said partitions; unions connecting the projecting ends of said pipes to form a continuous conduit extending upwardly within said cabinet; means for admitting cold air to the lower end of said conduit; means for preventing end movement of said pipes relative to said end partitions; an outlet from said conduit extending from the upper end of said cabinet, and a heat producing device directly beneath said conduit.
9. The combination of a cabinet having top, side and end walls of insulating material; metal partitions therein parallel with and spaced from the end walls of said cabinet; a plurality of pipes extending through both said partitions; unions connecting the projecting ends of said pipes to form a continuous conduit extending upwardly within said cabinet; means for admitting cold air to the lower end of said conduit; flanges formed on said end partitions and surrounding the outer ends of said pipes; an outlet from said conduit extending from the upper end of said cabinet, and a heat producing device directly beneath said conduit.
10. The combination of a cabinet formed of insulating material; an oil burner in the bottom thereof; end compartments entirely enclosed; a continuous winding conduit for the air to be heated disposed immediately above said burner in two vertical tiers; an exit pipe for the products of combustion leading from the back wall of the cabinet and near the bottom thereof; and a passage at the rear of said cabinet leading to said exit pipe from a point near the top of said cabinet.
- Signed by me at Marlboro, Massachusetts, this 20th day of February, 1930.
